United States Patent Office

Des. 202,569
Patented Oct. 19, 1965

202,569

SILVERWARE BASKET

Louis Maslow, Huntsville Road, Dallas, Pa.

Filed June 3, 1964, Ser. No. 80,269

Term of patent 14 years

(Cl. D44—29)

FIG. 2

I claim:

The ornamental design for a silverware basket, substantially as shown and described.
